(57) **CLAIM**

The ornamental design for a jewelry ring, as shown and described.

DESCRIPTION

FIG. 1 is a perspective view of a jewelry ring showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The bands with stipple shading illustrate a contrasting appearance from the bands without stipple shading.
